(57) **CLAIM**

The ornamental design for a handle grip for a cleaning apparatus, as shown and described.

DESCRIPTION

FIG. 1 is a front perspective view of a handle grip for a cleaning apparatus in accordance with the present design;

FIG. 2 is a front perspective view thereof;

FIG. 3 is a right side view thereof;

FIG. 4 is a left side view thereof;

FIG. 5 is a top view thereof; and,

FIG. 6 is a bottom view thereof.

In the drawings, the broken lines depict environmental subject matter only and form no part of the claimed design.
